CHOPPING MACHINE

Voldemar Borsakovsky, Montrouge, France,
assignor to Eugene Vincent, Paris, France

Application March 31, 1934, Serial No. 718,506
In France April 4, 1933

10 Claims. (Cl. 146—192)

The object of the present invention is an improved mincing machine of the type comprising a feeding device, such for example, as a grating or perforated plate, for the substance to be treated and a part capable of rotation provided with a certain number of knives or blades which cut the substance when it emerges from the orifices of said grating. The improvements which form the subject matter of the present invention consist in the following points:

1. The axis of the knife-carrier coincides with the axis of the feed device of the substance to be minced;
2. The grating, or perforated plate, constitutes a portion of a cylinder, the axis of which is the rotational axis of the system, in such a manner that the emergence of the substance to be minced occurs in a direction which is practically perpendicular to the driving axis;
3. The knives are positioned on the inner wall of an outer crown or cup which is concentric with the feed device of the substance to be minced;
4. The adjunction to the knife carrier cup of automatic contrivances for the admission of fluids (gases or liquids) with which it is desired to treat the substance reduced to fine particles, either with a view to cooling it or to impart to it any desired qualities (coloration, bleaching, etc.);
5. The peculiar method of mounting the knives in the wall of the rotating cup by means of inserted parts some of which are integral with said cup while others are removable and may be constituted, according to different cases, by one or by two parts, said parts being provided with suitable devices for fixing and gripping them, the whole assembly being designed so as to ensure perfect locking of the knives in their housings or slots, said locking being greater as the rotational speed of the cup becomes greater;
6. The peculiar method of mounting the inner portion of the machine with a view to obtaining the ready removal of the inner organs of said machine and, more especially, of the feed device of the substance to be minced, with a view, for instance, to cleaning the machine when it has been functioning for a certain period;

7. The insertion, between the inner wall of the hub of the fixed plate of the machine and the ball bearing of the main shaft, of a conical part slit along the whole of its length;
8. A variant of the machine, making it possible to evolve a double acting machine, in which said variant the substance, after having been chopped by a row of moving knives, solid with the rotating cup, passes into a mixing chamber which rotates

together with the cup and on emerging from said mixing chamber, said substance which has thus been flung away from the center, is chopped again by a second series of fixed knives mounted on the inner walls of the fixed drum of the machine.

In the attached drawings a certain number of embodiments of the invention have been shown in purely diagrammatic form as examples.

Figure 1 is a section of a first form of embodiment in which the feeding device of the substance to be chopped is driven by a helical gear driving wheel while the knife carrier device is driven by a vertical shaft electric motor;

Figure 2 is a section according to line II—II of Figure 1;

Figure 3 is a view, similar to that in Figure 1 of another form of embodiment in which the knife carrier crown is fixed;

Figure 4 is a part section, according to a vertical plane, of a first form of embodiment of the improved machine built according to the invention;

Figure 5 is a section according to line V—V of Figure 4. This figure shows the various inserted parts which make it possible to grip the knives in the corresponding slots;

Figure 6 is an end view of the rotating cup, it being assumed that the housing of the machine has been removed;

Figure 7 shows, in diagram, how a chopped substance, homogeneous in consistency, is obtained by the use of a large number of knives;

Figure 8 is a view, similar to that in Figure 1, of a variant comprising one row of moving knives and one row of stationary knives, and a rotating mixing chamber interposed between said two rows of knives.

In the form of embodiment shown in Figures 1 and 2, the substance to be chopped is fed, by hopper 1 to drum 2 whence it is drawn along (by a screw or by an Archimedean screw 3, mounted loose on shaft 4 and actuated by helical gear wheel 5), towards cylindrical grating 6. It is on issuing from the orifices of said screen that the substance undergoing treatment is chopped by knives 7 or blades imbedded in the inner wall of cup or crown 8 mounted on axis 9 which is an extension of shaft 4 of electric motor 11.

In the form of embodiment shown in Figure 3, the substance to be chopped drops, by gravity, from hopper 1 into rotating drum 12 which is provided, at the bottom, with a cylindrical grating 6. Under these conditions, during the rotation of drum 12, the substance to be chopped comes opposite each one of knives 7 of fixed cup 55

8' thus making it possible also to obtain very minute and regular chopping of the substance undergoing treatment.

In the form of embodiment shown in Figures 4 to 6, the substance to be chopped is likewise drawn along by a screw, or Archimedean screw, 3 mounted on main shaft 4. Said screw leads the substance towards the outlet opposite the knives, or blades, 7 which are imbedded in the inner wall 10 of cup or crown 8, mounted on axis 9 which is positioned on the prolongation of shaft 4.

Blades 12 are mounted on the bottom of rotating cup 8 and are intended to set up an intense draft of air when the device is functioning. Cool 15 air is thus drawn in through ports 13 and is forced towards annular space 14 provided between the stationary part of the machine and the inner wall of the rotating cup opposite knives 7.

20 Owing to the current of air which is thus automatically set up, and which is intensified by blades 12, it is possible to cool the mass to any desired degree in the course of the chopping operation. Instead of cool air it is likewise possible to introduce any gassy or liquid fluid in order to impart any desired properties to the products issuing from the machine. For this purpose shaft 9 is drilled to provide a channel 15 to which is connected a duct 16 opening out at 30 point 17 on the bottom of cup 8.

The fluid introduced in this manner is sprayed under the action of the current of air issuing from ports 13 and by centrifugal force. It reaches the knives under any desired head of 35 pressure.

A method of mounting the knives on the inner wall of rotating cup 8 has been shown in Figure 5. As is shown in this figure, knives 7 are positioned in suitable slots provided in the cup in such a 40 manner that they may be held in position by fixed inserts 18, which are integral with the inner wall of said cup, and by keys 19 and 20. Said keys 20 are made up of two parts and, with a view to ensuring perfect gripping of the knives 45 in their respective seatings, they are provided with a suitable clamping device such as that shown at 21 in Figure 5.

By this method of mounting the knives in their slots perfect gripping of the knives is obtained, 50 said grip becoming greater in proportion as rotation becomes more rapid. The particles of the substance chopped by said knives pass into the housing of the machine, under the action of centrifugal force, through orifices the section of 55 which is comparatively large as shown at point 22 in Figure 6.

The knives are sharpened on either side so that each knife provides two cutting edges which can be employed successively for chopping by merely 60 turning the blade over. The clearance between the knife edges and the corresponding outlet port can be adjusted by means of adjusting screw 21; said adjustment is effected when tightening up the keys or the inserts.

65 Owing to the great number of knives with which the machine is provided, particles which are of greater density which are flung out during the operation and which issue from any of orifices 22 become mixed with particles of lesser 70 density issuing from more or less neighbouring orifices so that, when chopping is completed, the mass is perfectly homogeneous.

Indeed, referring to the diagram illustrated in Figure 7 it will be noticed that each particle of 75 substance issuing from orifice 22, after being

chopped by knife 7, is flung, under the action of centrifugal force, against the wall of housing D, between points M and N, according to the specific weight of said particle. Let us assume that the comparatively heavy particles accumulate at point M, while the lighter particles accumulate at point N. At the same time one of the adjoining knives 7', which chop the substance which is positioned opposite orifice 22', flings the light particles on to point M, whereas the heavy particles are flung to point N, so that finally a perfectly homogeneous mixture of the particles is obtained at all points of the housing.

Another feature of the improved machine which forms the subject matter of the invention 15 is its compact construction and the arrangement of its components which permits, in particular, of ready dismantling of the components positioned inside the machine when, for instance, it is desired to clean the machine after it has been 20 working for a certain period. For this purpose, according to the invention, stationary plate 23 and rotating cup 8, the latter being held in position by means of a nut 24, are positioned respectively on main shaft 4 of the machine and 25 on axis 9 which constitutes an extension to said main shaft 4. Between the inner wall of hub 25 of plate 23 and ring 26 which is shrunk on to ball bearing 27, a conical part 28, slit along the whole of its length, is inserted and is, in turn, 30 held fast in position by nut 29.

Finally, the device comprises a third nut 30 which serves to clamp plate 23 to the main body of the machine. Owing to this method of mounting, and more particularly to the application of the three nuts 24, 28 and 30, the dismantling of 35 the machine is rendered particularly easy. Indeed, it is obvious that when these three nuts are removed it becomes possible to withdraw plate 23 together with conical part 28 and feed 40 screw 3, the bore of which is of greater diameter than the outer diameter of ring 26 which is solid with ball bearing 27.

The form of embodiment shown in Figure 8 differs from the form of embodiment shown in 45 Figure 4 by the fact that it is provided with two rows of knives 7 and 7' one of which is movable and solid with cup 8 while the other is stationary and solid with a component fixed to the machine; mixing chamber 31, which is integral with said 50 cup, being interposed between said two rows. This form of embodiment makes it possible to obtain very minute chopping.

The characteristic feature of the improved machine which forms the subject matter of the 55 invention resides in the fact that it makes it possible, at the same time, to reduce the substance under treatment to a very fine powder and to project the powder obtained in this way by means of a current of fluid at a pressure which can be 60 adjusted.

The arrangement which has just been described and represented in the drawings is given merely as an example; but it is not so limited and it will be understood that various modifications in the form and details of the device illustrated may be made by those skilled in the art and without departing from the spirit of the invention. Thus, any other similar form of mounting the knives may be substituted to that hereinabove described, for instance one in which the rows of knives form a certain number of portions of cylinders, each constituted by an undetermined number of knives and keys, or inserts, made in one piece, the clamping of said portions 70 75

- of cylinders being obtained by means of movable keys, made of one part or of two parts, as hereinabove set forth. Similarly, instead of the screw, or Archimedean screw represented in Figures 1 to 5, it is possible to provide for the feeding of the substance to be treated by any other suitable means and, more particularly, by the action of centrifugal force, by making the means, which feeds the substance, movable.
10. What I claim is:
1. A chopping machine, comprising a feeding device in the form of a rotating helix for feeding the substance to be chopped, a co-axial knife-supporting member, and means for rotating said helical knife-supporting member with respect to the feeding device, the knives being so disposed on the knife-supporting member that their edges are substantially parallel to the axis of rotation and are disposed adjacent the periphery of the feeding device, the knife-supporting member being somewhat bowl-shaped and being adapted to introduce a current of air into the space between it and the feeding device and adjacent the knives at the time that the latter are performing their cutting operation, the current of air striking the substance at the moment when particles are being cut therefrom.
  2. A chopping machine, comprising a feeding device in the form of a rotating helix, a coaxial knife-supporting member, the latter being somewhat bowl-shaped, means for rotating said knife-supporting member with respect to said helical feeding device, the knives being so disposed on said knife-supporting member that their cutting edges are substantially parallel to the axis of rotation and are arranged adjacent the periphery of the feeding device, and openings in the bottom of said knife-supporting member whereby air is sucked into the space between the knife-supporting member and the feeding device and adjacent the knives during the rotation of the said rotatable member, the current of air striking the substance to be chopped at the moment when particles are being cut therefrom, the said current of air being drawn in through the openings provided in the bottom of the knife-supporting member, this air being directed into the annular space comprised between the knife-supporting member and the circumference of the rotating helix.
  3. A chopping machine, comprising a feeding device, a coaxial knife-supporting member, the latter being somewhat bowl-shaped, means for rotating said knife-supporting member with respect to said feeding device, the knives being so disposed on said knife-supporting member that their cutting edges are substantially parallel to the axis of rotation and are arranged adjacent the periphery of the feeding device, openings in the bottom of said knife-supporting member whereby air is sucked into the space between the knife-supporting member and the feeding device and adjacent the knives during the rotation of the said rotatable member, and blades also disposed interiorly of the bottom of said knife-supporting member for creating turbulence of the incoming air.
  4. A chopping machine, comprising a feeding device in the form of a rotating helix, a coaxial knife-supporting member, means for rotating said feeding device and said knife-supporting member relative to each other, the said helical means including a shaft common to the two elements, the knives being so disposed on said knife-supporting member that they are substantially parallel to the axis of rotation and are arranged adjacent the periphery of the feeding device, the said knife-supporting member being substantially bowl-shaped and the said knife-supporting member and shaft permitting the conduits to cooperate between themselves, and to extend from the interior towards the annular space provided between the vertical part of the knife-supporting member and the circumference of said rotating helix, this space comprising the region in the immediate neighborhood of the sides of the knives, in order to introduce a fluid capable of mixing with the particles detached from the material being cut.
  5. A chopping machine, comprising a feeding device, a coaxial knife-supporting member, means for rotating said feeding device and said knife-supporting member relative to each other, the said means including a shaft common to the two elements, the knives being so disposed on said knife-supporting member that they are substantially parallel to the axis of rotation and are arranged adjacent the periphery of the feeding device, the knife-supporting member being substantially bowl-shaped, and the said knife-supporting member having means therein for introducing a current of air during the operation of the machine into the space between said knife-supporting member and said feeding device and adjacent the region of the knife edges, and cooperating conduits in said shaft and said knife-supporting member for introducing a fluid from the exterior so that it can be thrust by the air current against the cut particles of the substance to be chopped, to treat the latter.
  6. A chopping machine, comprising a feeding device, a coaxial knife-supporting member, the latter being somewhat bowl-shaped, means for rotating said feeding device and said knife-supporting member with respect to the other, the knives being so disposed on said knife-supporting member that their cutting edges are substantially parallel to the axis of rotation and are arranged adjacent the periphery of the feeding device, a mixing chamber being provided between the knives and the wall exterior of the knives, the said mixing chamber being formed integral with the said bowl.
  7. As an element of a chopping machine, a cylindrical knife-supporting member having an upturned periphery, knives disposed in said upturned periphery with their cutting edges substantially parallel to the longitudinal axis of said member, and locking strips removably fitted on each side of said knives and between adjacent knives, for locking the knives into position.
  8. In a chopping machine, a feeding device for the substance to be chopped, a casing about said feeding device and having openings disposed about the side thereof near the bottom, a clamp plate forming the bottom of said casing and cooperating with the feeding device to thrust the substance to be chopped outwardly through said openings, a shaft extending centrally through said feeding device, a ball bearing on said shaft, a ring about said ball bearing, and a wedge forced between said ring and said clamp plate, to fix the latter in place.
  9. In a chopping machine, a feeding device for the substance to be chopped, a casing about said feeding device and having openings disposed about the side thereof near the bottom, a clamp plate forming the bottom of said casing and cooperating with the feeding device to thrust the substance to be chopped outwardly through said

- openings, a shaft extending centrally through said feeding device, a ball bearing on said shaft, a ring about said ball bearing, a wedge forced between said ring and said clamp plate, to fix the latter in place, a nut for securing said ball bearing on said shaft, a second nut abutting against clamp plate and locking the wedge in position, and a third nut serving to clamp the plate against the casing.
- 10 10. A chopping machine, comprising a feeding device for the substance to be chopped, a coaxial knife-supporting member, means for rotating said device and said knife-supporting member with respect to each other, a casing about said feeding device and having openings therein near

the bottom thereof, an annular skirt extending outwardly from the casing near the bottom thereof, and having a downturned flange at its outer edge, the said downturned flange having openings therein, knives supported in said last-mentioned openings, the said flange and bottom of the casing proper forming a recess, the said knife-supporting member having a cup received in said recess, knives supported in said cup adjacent the first openings, and a mixing chamber in said cup extending rearwardly from the knives therein to the knives in the said flange, thereby ensuring thorough mixing of the chopped particles.

VOLDEMAR BORSAKOVSKY. 15
